UNITED STATES PATENT OFFICE.

EZRA A. BURRELL, OF SALT LAKE CITY, UTAH.

TROUSERS HANGER AND STRETCHER.

SPECIFICATION forming part of Letters Patent No. 737,335, dated August 25, 1903.

Application filed October 30, 1902. Serial No 129,474. (No model.)

To all whom it may concern:

Be it known that I, EZRA A. BURRELL, a citizen of the United States, residing at Salt Lake City, in the county of Salt Lake and State 5 of Utah, have invented certain new and useful Improvements in Trouser Hangers and Stretchers; and I do declare the following to be a full, clear, and exact description of the invention, such as will enable others skilled 10 in the art to which it appertains to make and use the same.

My invention is an improved trousers stretcher and hanger; and it consists in the peculiar construction and combination of devices hereinafter fully described and claimed.

The object of my invention is to provide a cheap, simple, and efficient article of this character which is adapted for stretching and hanging trousers of various sizes and which 20 may be conveniently hung to any suitable object, such as a hat-hook, nail, string, rod, or wire.

The accompanying drawing is a perspective view of a trousers stretcher and hanger embodying my improvements, showing the same in use.

In the embodiment of my invention I provide a yoke or stretcher-rod 1, which is here shown as made of a single piece of wire bent at 30 its center to form an eye 2 on its upper side and bent at its ends to form downwardly-extending hooks 3. A suspending-hook 4 is attached to the eye 2 at the center of the yoke, and to the hooks 3 are attached suitable elastic hangers 5, of which two pairs are employed, the said hangers being provided at their upper ends with eyelets 7 to receive and engage the hooks 3 of the yoke. At the lower ends of the elastic hangers are spring-clasps 6. The 40 upper end of one arm of each clasp is attached to the lower end of one of the elastic hangers, as shown.

In operation the trousers are suspended in an inverted position, with the bottoms of their legs engaged by the clasps 6, as shown in the 45 drawing. The tension of the elastic or spring hangers is such as to stretch the trousers-legs and keep them in proper shape.

It will be understood that my improved trousers stretcher and hanger occupies but 50 very little space and that a number of them may be employed in a comparatively small closet or wardrobe for stretching or hanging a number of pairs of pantaloons.

From the foregoing description, taken in 55 connection with the accompanying drawing, the construction, operation, and advantages of my invention will be readily apparent, it is thought, without requiring a more extended explanation.

Various changes in the form, proportion, and the minor details of construction may be resorted to without departing from the principle or sacrificing any of the advantages of 60 this invention.

Having thus fully described my invention, what I claim as new, and desire to secure by Letters Patent, is—

A trousers-stretcher comprising a yoke having depending hooks at its ends, two pairs of 70 elastic hangers having eyes at their upper ends engaging the said hooks, one pair of the hangers depending from each of said hooks, and spring-clasps at the lower ends of the said elastic hangers, one arm of each of the spring-clasps being attached to one of the said elastic hangers, substantially as described.

In testimony whereof I have hereunto set my hand in presence of two subscribing witnesses.

EZRA A. BURRELL.
